U.S. Appl. No. 29/438,075, Applicant: Beom-Seok Lee et al., filed Nov. 26, 2012 entitled Lower Disk for Checking Body Fluid.

* cited by examiner

Primary Examiner — Anhdao Doan

(74) *Attorney, Agent, or Firm* — Flynn, Thiel, Boutell & Tanis, P.C.

(57) **CLAIM**

The ornamental design for a disk for checking body fluid, as shown and described.

DESCRIPTION

FIG. 1 is a top front perspective view of a disk for checking body fluid showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a top front perspective view of the lower disk for checking body fluid when the upper disk of the FIG. 1 disk is removed;

FIG. 9 is a front elevational view thereof;

FIG. 10 is a rear elevational view thereof;

FIG. 11 is a left side elevational view thereof;

FIG. 12 is a right side elevational view thereof;

FIG. 13 is a top plan view thereof; and,

FIG. 14 is a bottom plan view thereof.
